ATTACHMENT FOR SEWING MACHINES

Irene Brauer, M. Gladbach, Germany, assignor to Fremaco International, Inc., Chicago, Ill., a corporation of Illinois

Filed Nov. 6, 1956, Ser. No. 620,604

Claims priority, application Germany Dec. 19, 1955

5 Claims. (Cl. 112—77)

This invention relates as indicated to an attachment for sewing machines, and more particularly to attachments for making decorative stitches or buttonholes.

In the past, if it were desired to produce decorative stitches or buttonholes, by means of attachments attached to the fabric presser foot post of a simple sewing machine, the layer of stitches had to be additionally positioned sideways. In the case of buttonholes, the positioning was done by leaving the needle with its top in the fabric after having sewn the first buttonhole hem, lifting the fabric presser post together with the attachment (attached to the fabric presser post) and turning the fabric by 180° around the top of the needle in the fabric, getting the needle out of the fabric, and then positioning the fabric sideways. After putting down the fabric presser post, then, beside the first buttonhole hem the next one could be made. In other words, the positioning of the stitch field was made by moving a suitable mechanism guided by hand, after having sewn a certain number of zig-zag stitches, which shifts the sewing foot with the fabric underneath it sideways in sewing direction. The thus newly created stitch is again sewn upon with a number of zig-zag stitches, whereupon the process of shifting the sewing foot, as mentioned above, is repeated. Here also the positioning of the stitch field is controlled by hand. The thus produced decorative seams, although produced by tedious and long work, were not exact and even, since the necessary counting of the individual stitches demanded unusual attention. Naturally, the positioning of the stitch field might be effected by hand during the sewing process, but it was practically impossible, even with trained operators with the greatest attention to produce continuously clean, and even, decorative seams.

It is, therefore, an object of the invention to provide an attachment for sewing machines for producing zig-zag stitches.

It is a further object of the invention to provide an attachment which effects automatically the positioning of the stitch field, so that without any special knowledge or training, decorative stitches can be achieved easily and conveniently, no matter how long, and with precise symmetry.

It is a still further object of the invention to provide an attachment that is conveniently and inexpensively manufactured.

Further objects and advantages of this invention will become evident as the description proceeds and from an examination of the accompanying drawing, which illustrates one embodiment of the invention and in which similar numerals refer to similar parts throughout the several views.

In the drawings:

Figure 1 is a view in elevation of the device embodying the invention.

Figure 2 is a plan view of the device shown in Figure 1.

Figure 3 is a view in section taken along lines 3—3 of Figure 2.

2

Figure 4 is a view in section taken substantially along line 4—4 of Figure 2 with the fork lever broken away.

Figure 5 is an exploded view of the device shown in Figure 1.

Referring now to the drawings, reference numeral 10 indicates generally the attachment embodying the invention for making decorative stitches or for sewing buttonholes.

A supporting member 11 is adapted to be securely fastened to the presser foot post of a sewing machine. Journalled in the supporting member is a shaft 12. Mounted on the shaft 12 on opposite sides of the supporting member 11 are a pair of plates 14, 15, having on the inner face thereof cams 16, 17. The shaft and the cams are advanced step by step by a stepping mechanism. The stepping mechanism includes a fork lever 20 adapted to be reciprocated by the moving needle post on the sewing machine in a well known manner. The shaft is advanced by a pawl mounted on the fork lever that engages a ratchet 22 mounted on shaft 12.

The presser foot 30 swings back and forth to move the material under the needle in a predetermined manner. The presser foot is suspended on an arm 31. At the rearward portion of the arm 31 is mounted a cam follower 32 which is swung back and forth by the rises and dwells on cams 16, 17. In the presser foot arm 31, between the cam follower 32 and the presser foot 30, is an elongated slot 33.

A slider bar 36 has an upwardly bent end 37 that projects through the slot 33 and serves as a pivot for the presser foot arm 31. Thus, as the cam follower 32 is swung back and forth by cams 16, 17, the presser foot arm 31 swings about pivot 37 on the slider bar 36. The slider bar has a handle portion 38 so that it may be manually adjusted to position the pivot 37 at a selected location. In this way the amount of swinging motion of the presser foot 30 may be adjusted or varied. An elongated slot 39 is formed in slider bar 36.

Depending from supporting member 11 through slot 33 of presser foot arm 31, and slot 39 of slider bar 36, is post 40. A supporting plate is mounted on the bottom of the post for holding a slider bar and presser foot arm in position. The plate 41 is retained on the post 40 by a pin 42.

Cam 50 is mounted on shaft 12 opposite the fork lever 20. Cam 50 has laterally displaced marginal edge portions 51. A cam follower member 53 has a forked portion 54 for actuation by cam 50. The cam follower member 53 is pivoted about the pin 55 mounted in the supporting member 11. A slot 56, formed in the cam follower member 53, receives the upper end of pivot 37 of slider bar 36. As cam 50 is rotated, the cam follower 53 is laterally displaced by the contour on the marginal edges of cam 50. As the cam follower is displaced, it also displaces the pivot 37 of slider bar 36. Thus, the presser foot arm 31 as it swings about pivot 37 is displaced sideways during the sewing operation, according to design of cam 50.

Cam 50 is removably mounted on shaft 12 by a manually operable thumb screw in the form of a screw with a knurled head 59. A number of cams similar to 50 may be supplied with the sewing attachment, and substituted by the operator by merely removing the thumb screw and placing on the shaft 12 the proper cam for the desired decorative stitch.

A bent plate 60 may partially enclose the opening between plates 14, 15. The plate is fastened to supporting member by a screw 61.

From the foregoing the operation of the attachment should be apparent. The fork lever 20 is driven up and down in the normal manner by the needle post of the sewing machine, advancing the cams 16, 17. The ad-

vancement of the cams 16, 17, swings the presser foot arm 31 through actuation of the cam follower 32 and shifting the fabric beneath the presser foot 30 diagonally to the sewing direction in a manner such that zig-zag stitches are achieved. The swinging of the presser foot arm 31 is about pivot 37 of slider bar 36. The contour formed on cam 50 displaces laterally the pivot 37, also diagonally to the sewing direction of the machine. By action of the sideways displacement of the pivot 37, the presser foot arm 31 and with it the fabric beneath the presser foot 30 is additionally pushed diagonally to the sewing direction of the machine. With this, the automatic sideways adjustment stitch positions of the normal zig-zag stitch during a sewing operation are achieved. Depending upon the construction of cam 50, which may be manually exchanged without difficulty, decorative stitches can be obtained by inexperienced operators.

In the drawing and specification there has been set forth a preferred embodiment of the invention, and although specific terms are employed, these are used in a generic and descriptive sense only, and not for purposes of limitation. Changes in form and the proportion of parts, as well as the substitution of equivalents are contemplated, as circumstances may suggest or render expedient, without departing from the spirit or scope of this invention as further defined in the following claims.

I claim:

1. An attachment for sewing machines adapted to be fastened to the presser foot post of a sewing machine and driven by the needle bar comprising a supporting member, an adjustable pivot member, a presser foot supported for movements about said pivot member, a rotatable shaft, means adapted to be associated with a needle post for advancing said shaft, first cam means mounted on and rotated by said shaft for moving said presser foot about said pivot member to produce zig-zag stitches, second replaceable cam means removably mounted on one end of said shaft for transversely shifting said pivot member, and a manually operable thumb screw member for removably securing said second replaceable cam to said shaft, whereby the stitching pattern may be varied by manually substituting different cams for said second replaceable cam.

2. An attachment for sewing machines adapted to be fastened to the presser foot post of a sewing machine and driven by the needle bar comprising a supporting member, a pivot member, a presser foot supported for movements about said pivot member, a shaft, means adapted to be associated with a needle post for advancing said shaft, first cam means rotated by said shaft for moving said presser foot about said pivot member, second replaceable cam means removably mounted on one end of said shaft for transversely shifting said pivot member, and a manually operable thumb screw member for removably securing said second replaceable cam to said shaft, whereby the stitching pattern may be varied by manually substituting different cams for said second replaceable cam.

3. An attachment for sewing machines adapted to be fastened to the presser foot post of a sewing machine and driven by the needle bar, comprising a supporting member adapted to be fastened to the presser foot of a sewing machine, a pivot member, a presser foot supported for oscillatory movement about said pivot member, a shaft, means adapted to be associated with a needle post for rotating said shaft, first cam means secured to said shaft for rotation therewith, first follower means secured to said presser foot in operative association with said first cam means, said first follower means oscillating said presser foot about said pivot upon rotation of said first cam means, second replaceable cam means removably mounted on one end of said shaft for rotation therewith, second follower means operatively associated with said second cam means, said second follower means

engaging said pivot member for transversely shifting said pivot member upon rotation of said second cam means, and a manually operable thumb screw member for removably securing said second replaceable cam to said shaft, whereby the stitching pattern may be varied by manually substituting different cams for said second replaceable cam.

4. An attachment for sewing machines adapted to be fastened to the presser foot post of a sewing machine and driven by the needle bar, comprising a support member adapted to be fastened to the presser foot post of a sewing machine, a pivot member, arm means pivotally supported intermediate its ends on said pivot member, a presser foot mounted on said arm means, a shaft, means adapted to be associated with a needle post for rotating said shaft, first cam means secured to said shaft for rotation therewith, first follower means mounted on said arm means in operative association with said first cam means, said first cam means, said first follower means oscillating said arm means about said pivot member upon rotation of said first cam means, second replaceable cam means removably mounted on one end of said shaft for rotation therewith, second follower means operatively associated with said second cam means, said second follower pivotally secured to said support member and receiving said pivot member for transversely shifting said pivot member upon rotation of said second cam means, and a manually operable thumb screw member for removably securing said second replaceable cam to said shaft, whereby the stitching pattern may be varied by manually substituting different cams for said second replaceable cam.

5. An attachment for sewing machines adapted to be fastened to the presser foot post of a sewing machine and driven by the needle bar, comprising a supporting member adapted to be fastened to the presser foot post of a sewing machine, a pivot member, arm means pivotally supported intermediate its ends on said pivot member for oscillatory movement thereon, a presser foot supported on said arm means, a shaft, means adapted to be associated with a needle post for rotating said shaft, first cam means secured to said shaft for rotation therewith, first follower means mounted on said arm means in operative association with said first cam means, said first follower means oscillating said arm means about said pivot member upon rotation of said shaft, second replaceable cam means removably mounted on one end of said shaft for rotation therewith, second follower means operatively associated with said second cam means, said second follower means engaging said pivot member for transversely shifting said pivot member upon rotation of said second cam means, and means for longitudinally moving said pivot member with respect to the ends of said arm means, and a manually operable thumb screw member for removably securing said second replaceable cam to said shaft, whereby the stitching pattern may be varied by manually substituting different cams for said second replaceable cam.
